C. R. HOYT, OF NEW YORK, N. Y.

Letters Patent No. 71,758, dated December 3, 1867.

APPARATUS FOR IRONING CLOTHES.

The Schedule referred to in these Letters Patent and making part of the same.

TO ALL WHOM IT MAY CONCERN:

Be it known that I, C. R. Hoyt, of the city, county, and State of New York, have invented a new and improved "Machine for Ironing or Smoothing Clothes, Textile Fabrics, &c.;" and I do hereby declare that the following is a full, clear, and exact description thereof, which will enable others skilled in the art to make and use the same, reference being had to the accompanying drawings, forming part of this specification, in which—

Figure 1 is a plan or top view of the machine.

Figure 2, a longitudinal vertical section, taken in the plane of the line x x , fig. 1.

Figure 3, a central longitudinal vertical section, taken in the plane of the line y y , fig. 1.

Figure 4, a transverse vertical section, taken in the plane of the line z z , fig. 1.

Similar letters of reference indicate like parts.

In the machine embraced by the present invention the clothes or fabrics to be ironed or smoothed are properly laid upon an endless travelling-apron or belt, and by it carried to the ironing-roller employed for smoothing the same, which roller is heated in any suitable manner, the frame in which the endless travelling-apron is arranged and moves being so hung that, when desired, in consequence of the seams in the garments, or for any other reason, it can be depressed sufficiently to relieve such portions of the garments from the pressure of the ironing-roller without interfering with the travel of the endless apron, as will be obvious from the following detail description thereof, reference being had to the accompanying plate of drawings hereinbefore referred to.

A, in the drawings, represents the framework of the machine, which is to be of any suitable construction to receive the working parts of the same. B, a frame placed in a horizontal position, and extending in the direction of the length of the machine, which frame consists of a board, C, with a strip, D, along each edge, projecting from each end of the same. Between the two projecting strip-ends, at the same and both ends of the frame, are rollers, E E, turning in bearings of the same, over and around which, passing both under and below the central board C, passes an endless travelling-apron, G, of a width equal to the said board, or nearly so. The frame B at one end, H, is hung in the framework A, between the two uprights, I, of the same, with the other end, J, resting upon spiral springs, K, around and about the posts, L, of the fixed cross-bar, M, of the framework, on which posts such end of the frame moves up and down, when pressure is brought to bear upon and released from it, in any proper manner. On one end of each of the rollers E is a similar grooved pulley, N, from both of which passes an endless belt, O, to and around the groove of the transverse horizontal driving-shaft, P, turning in suitable bearings of the framework, and with a crank-handle, Q, upon its outer end for turning it. Q², a gear-wheel secured to shaft P, the teeth of which interlock with a smaller gear-wheel, R, upon a transverse horizontal shaft, S, turning in bearings of the framework, with the teeth, T, of which interlocks a gear-wheel, U, secured to the outer end of a shaft, V, having a fan-blower, W, secured to it, and turning within a suitable box or chamber, X, open upon its two sides, and communicating, through a spout, Y, with the interior of the furnace-box, Z, below its grate, A², for the purpose of producing a draught up through the combustible products in its fire-pot, B², and thus produce a better and more perfect combustion of the same. In the spout Y is a damper, C², which, by opening or closing the same, regulates the current of air through it to the furnace-box. D², an ironing-roller secured to transverse shaft S, hereinbefore referred to, and revolving in conjunction with it, which roller is placed below the fire-plate, E², of the furnace fire-pot, and between it and the endless travelling-apron G, with both of which it revolves in contact.

Having thus described the particular construction and arrangement of the various parts composing my machine, I will now explain the manner of its operation.

The clothes or fabrics to be ironed are laid upon the endless apron, and by means of it carried to the ironing-roller D², which, revolving and being heated by contact with the fire-plate of the furnace-box, irons and then smooths such clothes or fabrics, when, after having passed under the said roller, they are removed from the apron, and again laid in proper position upon it for being again ironed by the said roller or not, according as may be deemed necessary or desirable, the endless-apron frame, when a heavy seam is passing under the roller, or for any other desired purpose, being depressed by bearing down upon its end resting upon the springs, so as to relieve such seam from being pressed between the ironing-roller and the apron.

In lieu of heating the ironing-roller in the manner described, it may be made hollow, and heated by properly admitting steam thereto; and therefore I do not intend to limit myself to any particular manner of heating it.

I claim as new, and desire to secure by Letters Patent—

1. The ironing-table B, whose free end rests upon the posts L, and spring K, ironing-roller D², upon shaft S, revolving in contact with the curved fire-plate E², fan-blower W, and driving-shaft P, all arranged as described for the purpose specified.

2. The ironing-table B, pivoted to the frame A at one end, and whose outer end rests upon the posts L, and spring K, as and for the purpose specified.

3. The combination of the fan-blower W with the yielding spring ironing-table B, ironing-roller D², and fire-pot B², substantially as described for the purpose specified.

4. The arrangement upon the frame A of the driving-shaft P, pinion-wheel Q², shaft S, wheels R T U, fan-blower W, grooved roller N, cord O, furnace B², ironing-roller D², curved fire-plate E², yielding ironing-table B, as herein set forth for the purpose specified.

C. R. HOYT.
